UNITED STATES PATENT OFFICE.

RALPH A. HOWE, OF WASHINGTON, DISTRICT OF COLUMBIA.

NEEDLE.

Application filed April 28, 1926. Serial No. 105,247.

This invention relates to a knitting needle designed to be manipulated by hand for the purpose of repairing runs or ravel in knitted articles or fabric such for example as 5 stockings.

One of the objects of the present invention is to provide a needle for the purpose stated which may be rapidly manipulated to re-establish the loops in a run in a knitted 10 fabric and without the exercise of any particular skill or close attention on the part of the user of the needle, the needle being so constructed that one who has by practice acquired a knowledge of the length and 15 direction of the stroke to be imparted to the needle may rapidly manipulate the same without any likelihood of performing the task in an improper manner and may, on the other hand, re-establish the loops of a run 20 with such precision that the fact that the fabric has been repaired will not be perceptible to the eye.

Another object of the invention is to so construct the needle that the position which 25 it should be caused to assume in its operation will be the most natural position in which the needle would be held by the user so that having, by practice, properly determined the method of manipulating the 30 needle and the stroke to be given the same, one may perform perfect repair work in knitted fabric having a run therein, the operation of the needle, or rather the functioning of its component elements, being entirely 35 mechanical and depending upon no extraneous physical force such as magnetism.

The needle embodying the invention includes, as essential elements, a hook and a 40 latch for coaction therewith, and it is another important object of the present invention to so construct the latch that in the mere backward and forward reciprocation of the needle substantially on a line with its 45 axis, and by proper engagement with threads to be re-looped in a piece of knitted fabric in which a run has been produced, the latch will automatically function with accuracy to result in the perfect re-formation of the 50 loops.

Another object of the invention is to so construct the needle that but a single reciprocation thereof, that is to say, a forward and backward movement substantially in a 55 line with its axis, is required to form each

loop, so that the task of repairing a run in knitted fabric is capable of accomplishment in less time and with less labor than where, as in some previous instances, it has been necessary to impart two backward and forward strokes to the needle for the purpose of forming each loop.

Another object of the invention is to so construct the needle that the loops will be accurately and uniformly reformed so that 60 the re-established series of loops will completely eliminate the unsightly appearance of the run and restore the fabric to its original condition.

Another object of the invention is to provide a needle for the purpose set forth so constructed that it will be entirely mechanical in its operation when reciprocated by hand and will not be rendered more or less inoperative or inefficient if the fabric acted 70 upon by the needle carries any oily matter which might form an imperceptible and yet present film upon the surfaces of the elements of the needle.

In the accompanying drawings:

Figure 1 is an enlarged side elevation of the needle embodying the invention, the latch of the needle being shown in full lines in closed position and in dotted lines in 80 open position.

Figure 2 is a vertical sectional view on an enlarged scale illustrating the needle, a portion of the latch being shown in elevation and a portion in section, as also the hook 85 of the needle.

Figure 3 is a front elevation of the needle, the latch being closed.

Figure 4 is a similar view illustrating the latch open.

Figure 5 is a perspective view of the latch 95 removed from the needle shank.

Figure 6 is a schematic view illustrating on a much enlarged scale the fabric to be repaired and the manner in which the needle is engaged with a loop at the end of 100 the run in the fabric in the initial application of the needle to the fabric for the reformation of the loops.

Figure 7 is a similar view illustrating the needle at substantially the limit of its 105 forward stroke through the fabric and through the loops with which it is illustrated as engaged in Figure 6 of the drawings.

Figure 8 is a similar view illustrating the manner in which the first thread of the 110

run is engaged by the hook of the needle immediately prior to looping it to restore the loop therein.

Figure 9 is a similar view illustrating the new loop as formed and the position of the needle immediately after the commencement of the operation of forming the next loop.

The needle embodying the present invention comprises in general a hook member 10 and a latch member coacting therewith. The hook member includes a shank 1 provided with a handle 2 which may be of any desired contour and any desired material. The shank 1 is preferably circular 15 in cross section and, at its free end terminates in a hook which is indicated in general by the numeral 3, the shank being gradually tapered, as at 4, at and adjacent its juncture with said hook. The hook is 20 likewise preferably circular in cross section and is tapered to the extremity of its bill, which bill is indicated by the numeral 5. The bight of the hook extends or curves laterally from its juncture with the shank 1 25 and the extremity of the bill of the hook is presented toward the butt end of the shank, at which end the handle is located. The bill of the hook is tapered, as clearly shown in Figure 4 of the drawings, and one side of 30 the bill of the hook is more acutely inclined or beveled than the other side, as indicated by the numeral 6, so that the side 6 of the bill is more pronouncedly tapered than the opposite side thereof, and the purpose of 35 thus forming the bill of the hook will presently be more particularly pointed out. The shank 1 of the needle is formed in its side from which the hook 3 projects, with a narrow longitudinal channel indicated by 40 the numeral 7, and the numeral 8 indicates in general the latch member of the needle which includes a shank portion 9 disposed within the channel and supported upon a pivot pin 10 fitted through its end and 45 through the opposite side walls of the channel. The latch 8 comprises, in addition to the shank 9, a head 11 which is located at the free end of the latch and is preferably of approximately slender elliptical form, in 50 marginal contour, as shown in Figures 3, 4 and 5 of the drawings. The head 11 is preferably slightly and gradually rounded transversely at its outer side and likewise rounded in the direction of its extremity, 55 and the inner side of the said head 11 is formed with a shallow concavity indicated by the numeral 12. At this point, it will be observed by reference to Figures 1 and 3 of the drawings, that when the latch 8 is closed, the concave side 12 of its head 11 rests against the outer side of the bill of the hook 3 and that the said head of the latch is of approximately the same width at its intermediate portion as the diameter 60 of the bight of the hook, the head being so

proportioned that its extremity, in the stated position of the latch, projects a short distance beyond the point of engagement of the bill of the hook with the concave surface 12 of the head so that the extremity of 70 the head is slightly spaced from the outer side of the bill of the hook. The outer edge of the latch, or what may be termed the back of the latch, indicated by the numeral 13, extends preferably on a substantially 75 straight line, as shown in Figure 2 of the drawings, and merges with the outer surface of the head 11. As will be observed by reference to Figure 5, and likewise by reference to Figure 4 of the drawings, the shank 9 of the latch 8 is flat-sided at and adjacent the pivot 10 and of a thickness to freely fit within the channel 7 and yet be restrained from any lateral displacement, and from a point immediately adjacent the 80 rear end of the head 11, the said shank is gradually increased in thickness, both in the direction of its free end and likewise in the direction of its said back 13. It will likewise be noted by reference to the drawings, that that edge of the shank which is opposite the edge or back 13, and which is indicated by the numeral 14, extends on a line diverging from the line of extent of the said back 13 in the direction of the free 85 end of the latch. The latch is provided at its free end and inwardly of the extremity of the head 11, with a nose or hump 15 which preferably extends at an obtuse angle from the inner concave side of the head and is preferably rounded, as indicated by the numeral 16, and merges with the forward end of the inner edge 14 of the latch. This rounded portion of the nose or hump 90 constitutes an important feature of the present invention and it will be observed by reference to Figure 2 of the drawings, that when the latch is in the closed position shown in said figure, the inner edge portion of the latch is received within the lower 95 portion of the channel 7 and the concave side of the head 11 rests against the outer side of the bill of the hook 3, the rounded portion 16 of the nose or hump 15 of the latch being located close to the forward side 100 of the tapered portion 4 of the shank of the needle and curving outwardly therefrom. The purpose of this forming the nose or hump of the latch will presently be fully explained. 105

The forward side of the shank of the needle or, in other words, the side on which the hook and latch are fitted, is formed with a shallow gradually inwardly curved recess 17 extending substantially from the upper end of the channel 7 to a point slightly spaced above the pivot pin for the latch and it will be observed by reference to Figures 1 and 4 of the drawings, that when the latch is in its open position, as shown 110

in dotted lines in Figure 1 and full lines in Figure 4, its back edge portion 13 will seat in the upper portion of the channel 7 with the head 11 resting in the upper portion of the recess 17 and with the rounded outer side of the extremity of the head projecting slightly in spaced relation to the said side of the shank at the upper end of the said recess, the said extremity of the head 10 of the latch, in this position of the latch, being spaced just sufficiently far in the manner stated, to provide for the engagement of a thread therewith for the purpose of closing the latch in the backward movement of 15 the needle through the fabric, as will presently be explained, and thus effect closing of the said latch.

Figures 6, 7, 8 and 9 illustrate the manner in which the needle embodying the invention 20 is employed, and in each of these figures there is schematically illustrated, on a very much enlarged scale, a piece of knitted fabric in which there is a run or ravel, and in each of these figures, the reference letter 25 *a* indicates the loop which is at the extreme end of the run, and in repairing the run by re-forming the loops, the needle is first arranged in the position shown in Figure 6 of the drawings, with its hook 3 engaging in 30 the loop *a* and with its latch 8 in full open position. Prior to such initial engagement of the needle with the fabric, the fabric is stretched over a support, preferably comprising a bowl of a white color having a circular rim and which may conveniently be an egg cup, and the fabric is so arranged that the run will extend over the bowl of the cup and the fabric is tensioned by grasping it about the outer surface of the cup and pulling downwardly. The advantages gained 35 by supporting the fabric in this manner are that its portion which is to be acted upon by the needle is tensioned, and the said portion is supported above the white surface of the 40 bowl of the cup thus affording ample room for manipulation of the needle and, at the same time, providing a white background against which the threads and loops of the fabric will be plainly visible. The needle 45 is then inserted diagonally and forwardly in the direction indicated by the arrow in Figure 6, through the loop *a*, until, as shown in Figure 7 of the drawings, the latch, in its open position, has passed through the 50 loop. The needle is then shifted backwardly in the direction of its length, as indicated by the arrow in Figure 7, and in this movement of the needle the loop *a* will engage behind the extremity of the head 11 of the 55 latch and between the same and the shank of the needle, thus throwing the latch forwardly to its closed position. As the latch moves to its closed position, in the backward movement of the needle, the thread *b* will be 60 thrown by the head of the latch into engage-

ment in the hook of the needle and will be so engaged when the latch is completely closed, as shown in Figure 8 of the drawings. The continued backward movement of the needle in the direction indicated by 70 the arrow in the said Figure 8, serves to pull the thread *b* through the loop *a* and thus form a loop in the said thread *b* as shown in Figure 9 of the drawings. Substantially at the moment this loop is formed it will 75 ride along the forward side of the tapered portion 4 of the shank of the needle as the needle is again started on its forward movement and, striking the rounded portion 16 of the nose or hump 15 of the latch, will 80 effect a sudden throwing open of the latch until it occupies its full open position, whereupon the needle is caused to continue on its forward movement until it has passed through the loop formed in the thread *b* to 85 the extent that the said loop will be engaged with the shank behind the extremity of the head of the open latch in the manner above noted with reference to Figure 7 of the drawings, the operation being now repeated 90 so as to pick up the thread *c* and form a loop therein engaging through the loop just formed in the thread *b*, and so on, until all of the threads of the run have had their 95 loops re-formed, the last loop formed being 100 permanently secured by whipping one or more stitches through it at the upper end of the repaired run. In the manipulation of the needle it is preferably reciprocated while occupying substantially the diagonal 105 position shown in Figures 6, 7, 8 and 9 of the drawings, and inasmuch as this is a very convenient position in which to hold the needle, and the needle latch is certain and automatic in its action, loops may be formed 110 with great rapidity and without the necessity of the painstaking care which has been required in the use of needles previously designed for this purpose. It will be evident 115 that due to the fact that the nose or hump 15 of the latch curves outwardly from the inner side of the tapered portion 4 of the shank of the needle, each loop through which the needle is moved in a forward direction, serves, through engagement with this portion of the latch, to effect instantaneous 120 throwing of the latch to full open position so that there is no likelihood of the extremity of the latch engaging the thread of the fabric in advance of opening of the latch by 125 the loop. In other words, owing to the position of the nose or hump with relation to the free end of the latch, automatic opening of the latch is effected by engagement of the thread of the loop with said hump before the free end of said latch engages or penetrates the fabric. Likewise, the latch is closed in an equally positive manner through the backward movement of the 130 needle through the loops previously formed

engaging between the rounded outer side of the head of the latch where it projects in slightly spaced relation to the upper end of the shallow recess 17 in the forward side 5 of the shank of the needle. Therefore, the movement of the latch into and out of closed position is a positive and accelerated one and effected entirely automatically in the back and forth passage of the needle through the 10 loops as they are successively formed in the fabric.

As previously explained, the taper of the side 6 of the bill of the hook is more pronounced than is the taper of the opposite 15 side of said bill of the hook and it will be evident that this is of advantage inasmuch as when the bill of the hook engages beneath the thread *b* for example, prior to assuming the position shown in Figure 8, and under 20 the action of the latch, the thread will pass freely over the said tapered side 6 of the bill of the hook inasmuch as this side is at such time substantially parallel to the line of extent of the thread.

25 While the needle embodying the invention is designed primarily for use in repairing runs in stockings and socks, its use is by no means limited to articles of hosiery, for it may be equally well employed in repairing runs in sweaters or any other knitted articles or fabrics.

It will be observed from the foregoing description of the invention that the needle is exceedingly simple in construction and 30 likewise very substantial, notwithstanding the fact that it will be of very small dimensions, in practice, and that there are no lateral stresses imposed upon the latch of the needle which might tend to distort the 35 same or weaken its connection with the shank of the needle. Likewise, it will be evident that the formation of the head of the latch is such that when the needle is pulled through the loops which have been 40 formed thereby, there is no possibility of the loops catching in the hook of the needle. On the other hand, the engagement of the threads of the run, in a piece of knitted fabric being repaired by the use of the 45 needle, is positively insured by the movement of the latch to closed position as the latch at this time serves to throw the thread into engagement in the bight of the hook of the needle.

50 It will be evident that due to the provision of the shallow recess 17 and likewise due to the proportioning of the latch 30 that the back of the shank of the latch will seat in the channel 7 with the head of the latch resting at its convex outer side in the 55 said recess at a point near the upper end thereof, it is possible to so proportion the parts that when the latch is open the needle will, at the point of location of the nose or 60 hump 15 and on a transverse line intersect-

ing the nose or hump and the needle shank, be reduced in thickness as compared with the thickness which the needle would possess at this point if it were not for the provision of said recess, so that less tension is imposed upon the thread in the formation of loops therein. Should the operator accidentally pick up two threads instead of one, the threads thus taken up may be dropped from the hook without entirely withdrawing the needle from engagement with the fabric, and the operation of the needle then continued in the proper manner.

In stating that the engagement of the looped thread with the nose or hump of the 80 latch effects an "accelerated" opening of the latch is meant that, owing to the position of the nose or hump with respect to the free end of the latch, the looped thread engages the latch sooner or quicker than if the shank 85 of the latch were of uniform diameter and consequently advances the time of the initial opening movement of said latch so that the opening of the latch is effected before the free end of said latch penetrates the fabric. 90

The term nose or hump applied to the part 15 on the latch is intended to cover any means which, when engaged by a thread, will move the latch to open position before the free end of said latch engages or penetrates the fabric. 95

Having thus described the invention, what I claim is:

1. A needle for repairing fabrics comprising a hook member, a latch member, and a hump on one of said members projecting toward the other member and engageable by a thread to open the latch before the free end of the latch engages the fabric. 100

2. A needle for repairing fabrics including a hook member and a freely movable pivoted latch member one of which is provided with a hump coacting with the other member and engageable by a thread to automatically open the latch before the free end 105 of said latch engages the fabric. 110

3. A needle for repairing fabrics having a shank and a hook, and a latch pivoted to the shank and movable to open and closed positions with relation to the hook, the said latch having a hump coacting with the shank, when the latch is in closed position, and engageable by a thread to open the latch before the free end of said latch engages the fabric. 115

4. A needle for repairing fabrics having a shank and a hook, and a latch pivoted to the shank and having a head at its extremity to engage the bill of the hook, the said latch being movable to open and closed positions with relation to the hook, the said latch being provided, inwardly of its said head, with a hump coacting with the shank, when the latch is in closed position, and engageable by a thread to open the latch be- 125 130

- fore the free end of said latch engages the fabric.
5. A needle having a shank and a hook at the end of the shank, and a latch pivoted to the shank and movable to open and closed positions with relation to the hook, the said latch having a hump coacting with the shank and provided with a curvilinear thread-engageable surface curved to extend outwardly 10 from the side of the shank when the latch is in closed position whereby to constitute means for effecting accelerated automatic opening movement of the latch through the engagement of the thread with the said hump when the needle is moved in contact with the thread.
6. A needle for repairing fabrics having a shank provided at its end with a hook, and a latch pivoted to the shank and movable 20 to open and closed positions with relation to the hook, the said shank having a shallow recess in its side from which the hook projects, the said latch having a head at its outer end engageable with the bill of the hook in the closed position of the latch and receivable within the recess in the open position of the latch, the outer surface of the said head of the latch being convexly curved in the direction of the length dimension of 30 the latch and a hump on the latch engageable by a thread to open said latch before the free end of the latch engages the fabric.
7. A needle for repairing fabrics having a shank provided at its end with a hook, and a latch pivoted to the shank and movable 35 to open and closed positions with relation to the hook, the said shank having a shallow recess in its side from which the hook projects, the said latch having a head at its outer end engageable with the bill of the hook in the closed position of the latch and receivable within the recess in the open position of the latch, the outer surface of the said head of the latch being convexly curved 40 in the direction of the length dimension of the latch whereby the extremity of the head will project in spaced relation to the recess in the said open position of the latch to be engageable by a thread when the needle is 45 moved in one direction, the said latch being provided, inwardly of the head, with a hump coacting with the shank, when the latch is 50 closed, and engageable by a thread as the needle is moved in the reverse direction to open the latch before the free end of said latch engages the fabric.
8. A needle having a hook, and a latch movable to open and closed positions with relation thereto and having a portion engageable by a thread to effect automatic accelerated opening of the latch, the bill of the hook being tapered and having one side more acutely tapered than the other, to permit of free passage of a thread to be looped, over the said bill of the hook.
9. A needle for repairing fabrics comprising a hook member, a pivoted latch member, and a hump on one of said members, the free end of the latch member being engageable by a thread to close said latch 70 member when the needle is moved in one direction and the hump being engageable by a thread when the needle is moved in the reverse direction to open the latch before the free end of said latch engages the fabric.
10. A needle having a shank provided with a tapered portion and a hook at the end of said tapered portion, and a latch pivoted to the shank and movable to open and closed positions with relation to the hook, said latch having a hump coacting 80 with the shank and extending transversely across the eye of the needle near the tapered portion of the shank whereby to constitute means for effecting accelerated opening movement of the latch through engagement of a thread with the said hump when the needle is moved in contact with the thread.
11. A needle for repairing fabrics having a hook member, and a latch member pivotally movable to open and closed positions with relation to the hook member, one of the said members having a hump projecting toward the other member and engageable by 95 a thread looped over the hook, the hump being so located with relation to the open side of the hook as to open the latch immediately following entrance of the loop into the open side of the hook and before 100 the free end of said latch engages the fabric.

In testimony whereof I affix my signature.

RALPH A. HOWE. [L. S.]
